UNITED STATES PATENT OFFICE.

ALBERT SCHMIDT, OF FLINT, MICHIGAN, ASSIGNOR TO CHAMPION IGNITION COMPANY, OF FLINT, MICHIGAN, A CORPORATION OF MICHIGAN.

SPARK-PLUG.

1,358,116.

Specification of Letters Patent.

Patented Nov. 9, 1920.

Application filed November 22, 1917. Serial No. 203,298.

To all whom it may concern:

Be it known that I, ALBERT SCHMIDT, a citizen of the Republic of France, residing at Flint, in the county of Genesee and State 5 of Michigan, have invented certain new and useful Improvements in Spark-Plugs, of which the following is a specification, reference being had therein to the accompanying drawings.

10 The invention relates to spark-plugs and comprises the novel construction as herein-after set forth.

In the drawings:

Figure 1 is a longitudinal section through 15 the plug;

Figs. 2 and 3 are cross-sections on lines 2—2 and 3—3 of Fig. 1.

A is the casing of a plug having the usual threaded nipple B for engagement with the 20 engine casing. C is the insulator and D is the electrode passing therethrough. The insulator C is provided with an inner end portion E, which is arranged within the portion B of the casing, and beyond this portion 25 the insulator is enlarged to form a shoulder F for fitting against a corresponding shoulder G on the casing. H is a gasket between the shoulders F and G for forming the gas seal, and I is an opposed shoulder on the 30 outer portion of the insulator, which is engaged by a turned-in flange J on the casing for holding the shoulders G and H in sealing relation to each other.

As usually constructed plugs of this type 35 have the portion of the insulator extending between the shoulders F and I of uniform diameter and fitting with a slight clearance within the outer casing. As the insulator is formed of material which is low in thermal conductivity it is desirable to limit the 40 size and mass of the same, particularly in the portion which is exposed to the flame and between the end of the electrode and the point of bearing F on the casing. On the 45 other hand, if the diameter of the insulator is too small the mechanical stress to which it is subjected in closing in the flange I (this operation being performed when the metal of the case is heated) and the subsequent stress exerted by this flange would 50 endanger cracking of the structure. I have

therefore constructed the insulator and casing with a portion of the former extending to the shoulder bearing F of restricted diameter, and above this bearing have enlarged the diameter of the insulator and correspondingly enlarged the casing to receive the same. As a result the annular bearing I over which the flange J is turned is sufficiently enlarged to more safely 60 stand the mechanical stresses, while at the same time the mass of material which is exposed to the heat is not enlarged. I have found that only a slight increase in the diameter of the upper portion of the insulator will greatly increase its mechanical strength and will correspondingly decrease the percentage of breakage. 65

What I claim as my invention is:

1. In a spark-plug, an insulator having an inner portion which is exposed to the heat, a portion beyond the same of larger diameter forming a shoulder and a portion beyond the shouldered portion of still larger diameter having an opposed shoulder formed thereon, all of said portions being integral in combination with a casing having a portion substantially fitting the inner shouldered portion of said insulator and providing a seat therefor, a portion enlarged in internal diameter for receiving the enlarged portion 75 of said insulator and an inturned flange on said enlarged portion for engaging the opposed shoulder on the enlarged portion of the insulator. 80

2. In a spark-plug, an insulator having an inner portion exposed to the heat, a cylindrical portion beyond the same enlarged in diameter with a conical seat portion intermediate said cylindrical portion and inner portion and a cylindrical portion beyond 90 said first-mentioned cylindrical portion of still greater diameter and providing at its outer end a shoulder opposed to the shoulder on the inner portion, all of said portions being integral in combination with a casing having a seat for said inner shoulder, a portion of internal diameter to substantially fit the cylindrical inner portion of the insulator, a portion of greater internal diameter for substantially fitting the enlarged cylindrical portion and a turned-in flange for 95 100

bearing against the shoulder on this latter portion.

3. In a spark plug, an insulator having an inner portion which is exposed to the heat and of restricted diameter, an enlarged portion having an annular shoulder adjacent to said exposed portion forming a sealing seat for engagement with the casing, and a still larger portion beyond said last-men-

tioned portion providing a substantial structure for projecting beyond the casing and also an opposed shoulder for a clamping bearing on said casing, there being no other points of bearing for said insulator upon said casing.

In testimony whereof I affix my signature.

ALBERT SCHMIDT.
